(57) CLAIM

The ornamental design for a beverage container, as shown and described.

DESCRIPTION

FIG. 1 is a perspective view of a beverage container showing the design.

FIG. 2 is a front elevation view of the beverage container of FIG. 1.

FIG. 3 is a side elevation view of the beverage container of FIG. 1.

FIG. 4 is rear elevation view of the beverage container of FIG. 1.

FIG. 5 is another side elevation view of the beverage container of FIG. 1.

FIG. 6 is a top plan view of the beverage container of FIG. 1.

FIG. 7 is a bottom plan view of the beverage container of FIG. 1.

FIG. 8 is another perspective view of the beverage container of FIG. 1.

FIG. 9 is another perspective view of the beverage container of FIG. 1.

FIG. 10 is another perspective view of the beverage container of FIG. 1.

FIG. 11 is a perspective view of a beverage container closure of the beverage container of FIG. 1.

FIG. 12 is a front elevation view of the beverage container closure of FIG. 11.

FIG. 13 is a side elevation view of the beverage container closure of FIG. 11.

FIG. 14 is a rear elevation view of the beverage container closure of FIG. 11.

FIG. 15 is another side elevation view of the beverage container closure of FIG. 11.

FIG. 16 is a top plan view of the beverage container closure of FIG. 11.

FIG. 17 is a bottom plan view of the beverage container closure of FIG. 11.

FIG. 18 is another perspective view of the beverage container closure of FIG. 11.

FIG. 19 is another perspective view of the beverage container closure of FIG. 11; and,

FIG. 20 is another perspective view of the beverage container closure of FIG. 11.

The broken lines in the drawings depict portions of the beverage container that form no part of the claimed design.
